United States Patent Office

Des. 200,461
Patented Mar. 2, 1965

200,461

WATER CLOSET

Dana W. Mox, Glenview, Ill., assignor, by mesne assignments, to Case Plumbing Manufacturing Co., Robinson, Ill., a corporation of Illinois

Filed Mar. 25, 1963, Ser. No. 74,126

Term of patent 14 years

(Cl. D4—5)

Fig. 1.

Fig. 2.

Fig. 3.

Fig. 4.

Fig. 5.

FIG. 1 is a top plan view of a water closet embodying my new design.

FIG. 2 is a front elevational view thereof.

FIG. 3 is a rear elevational view thereof.

FIG. 4 is a side elevational view thereof, viewed from the left hand side of the water closet as shown in FIG. 2.

FIG. 5 is a side elevational view thereof, viewed from the right hand side of the water closet as shown in FIG. 2.

I claim:

The ornamental design for a water closet, substantially as shown.
